UNITED STATES PATENT OFFICE.

HUGO BRACH, OF VIENNA, AUSTRIA-HUNGARY.

APPARATUS FOR USE IN ELEMENTARY ORGANIC ANALYSIS.

1,112,432.

Specification of Letters Patent. Patented Oct. 6, 1914.

Application filed March 5, 1914. Serial No. 822,784.

To all whom it may concern:

Be it known that I, HUGO BRACH, a subject of the Emperor of Austria-Hungary, residing at Vienna, Austria-Hungary, have invented new and useful Improvements in or Relating to Apparatus for Use in Elementary Organic Analysis, of which the following is a specification.

The time occupied by combustion when employing the old Liebig method, and the disproportionate relation between the small quantity of substance employed and the large consumption of gas or electric current, have led to various suggestions for improvements. Thus, for instance, Pregl reported recently on a process, according to which the combustion takes place very quickly and can be carried out with a single burner. Pregl connects to the last absorption tube a mercury gasometer to collect the products of combustion which have not been absorbed, and then disposes the gasometer in front of the combustion pipe, in order once more to force the gases filling the gasometer through the heated pipe. This process gives the desired result but has the important drawback that the analysis must be carried out with a few centigrams, as otherwise gas-holders of very large dimensions are required.

The apparatus according to this invention renders it possible to obtain a quick combustion, without it being necessary to use smaller quantities of substances than those used with the old Liebig method. This problem is solved by inserting with a tight joint the combustion pipe proper into a second, wider pipe, also charged with copper oxide, copper coils or the like, through which the gases escaping from the last absorption tube, are sent for completing the combustion.

The apparatus according to this invention is schematically shown in the accompanying drawing, in which--

Figure 1 shows an apparatus embodying the present invention, and Fig. 2 shows a modified form of apparatus.

As will be seen from Fig. 1 a calcium chlorid pipe *c* and a soda-lime pipe *d* (if desired a Denstaedt swan neck) is connected in the usual manner to the combustion pipe *a*. The escaping carbon monoxid and the carbonic acid which has not been absorbed, are returned through a connecting pipe *h* preferably surrounded by a protecting metal tube not shown in the drawing, to the front portion of the outer or jacket pipe *b*, in order

to be completely burned while passing therethrough, and to be absorbed in the soda-lime pipe *e* when escaping from the pipe *b*.

f is a straight calcium chlorid pipe, *g* a washing-bottle charged with a solution of palladium chlorid, in order to indicate the passage of the carbon monoxid and the speed of the combustion.

In the construction shown in Fig. 2, the insertion of a long connecting pipe *h* for returning the gas current, is avoided by connecting together the calcium chlorid pipe *c* and the soda-lime pipe *d* by means of a U-pipe *i* and arranging them one behind the other. The outlet pipe *j* of the soda-lime pipe *d* enters into the rear end of the jacket pipe *b*, so that the reversing of the gas current is produced without inserting a separate pipe. The absorption tubes *e*, *f* and the washing-bottle *g* are in this case, of course connected to the front end of the jacket pipe *b*.

It will be seen that the apparatus described is made up of two concentric tubes forming two combustion tubes or furnaces and that an absorption apparatus is provided for the gaseous products of combustion from each tube, the unabsorbed gases from the first absorption apparatus being subsequently passed through the second combustion tube and then through the second absorption apparatus. The gases are thus twice subjected to combustion conditions so that thorough combustion is secured, while the absorbable products of combustion are absorbed after each such combustion.

I claim:

1. An apparatus of the nature described comprising two concentric combustion tubes, one surrounding the other with a tight joint, two sets of absorption apparatus, and means for passing the gases from one of said tubes through one absorption apparatus and then through the other tube and the other absorption apparatus.

2. An apparatus of the nature described comprising an inner main combustion tube, an absorption apparatus for the gases escaping therefrom, an outer combustion tube surrounding said inner tube with a tight joint arranged to receive the unabsorbed gases from said absorption apparatus, and a second absorption apparatus for the gases escaping from said outer combustion tube.

3. An apparatus of the nature described comprising an inner main combustion tube

containing copper oxid, an outer combustion tube containing copper oxid surrounding said inner tube with a tight joint, an absorption apparatus, means for conducting the 5 gases from said main combustion tube through said absorption apparatus and said outer combustion tube, and an absorption

apparatus arranged to receive the gases from said last mentioned combustion tube.

HUGO BRACH.
